UNITED STATES PATENT OFFICE.

ERIK TIMANDER AND GÖSTA TIMANDER, OF ORSA, SWEDEN.

LIFTING APPARATUS FOR RAILWAY TRACKS.

Application filed April 29, 1925. Serial No. 26,648.

To all whom it may concern:

Be it known that we, ERIK TIMANDER and GÖSTA TIMANDER, subjects of the King of Sweden, residing at Orsa, Sweden, have invented new and useful Improvements in Lifting Apparatus for Railway Tracks, of which the following is a specification.

This invention relates to an apparatus for lifting of railway tracks or the like. The apparatus is of the type in which a stopping member is automatically pushed in under the track, when the latter is lifted by means of a double armed lever, and the object of the invention is the construction of an easily managed and effective lifting apparatus, in which the forward pushing of the stopping member may be easily effected, independently of the construction of the apparatus as a whole and of the load on the lever, while at the same time the apparatus is balanced as completely as possible, for preventing any oblique position of the stopping member or even any tendency of taking up such a position.

A constructional form of the invention is illustrated in the accompanying drawing. Fig. 1 is a longitudinal section on the line I—I of Fig. 2, Fig. 2 a plan view and Fig. 3 a cross section on the line

III—III of Fig. 1; Fig. 4 is a detail view.

The lever 1 which preferably is made from steel and of a rectangular cross section and its lower end is shaped as a hook 2 with horizontal studs 4. The bearing or lifting member for the said lever consists of two plates 5 suitably of a triangular shape and connected by stays, a fore and a back stay, 6 and 7, which may be in one piece. The upward turned, sloping edges 8 of these plates are provided with notches 9, in which the studs 4 may be pivoted. The distance between the two plates 5 is such, that the lever 1 can be moved freely between them. Outside each of these plates

5 another plate 9 of the same shape is situated, the sloping upper edge of which has the same inclination to the base edge as the corresponding edges of the plates 5. The edges of the plates 9 are provided with teeth 10 and the two plates 9 by means of a cross piece 11 are united to a lifting member. The cross piece 11 runs through the elongated slots 13 in the plates 5 which slots open in the edge of each plate 5 at 12. The two pairs of plates 5 and 9 thus are connected in such a manner that

they can be disengaged from one another and at the same time they are movable horizontally in relation to one another, which movement, however, is limited by means of the slots 13, so that it becomes a little larger than the horizontal distance between two adjacent notches 8 in the plates 5.

The lifting member 5 as well as the stopping member 9, 11 are movable upon a base plate 20, provided with a longitudinal groove 14 in which the stays 6 and 7 of the lifting member 5 project. The stopping member 9, 11 is provided with angular flanges 15 forming guides for other flanges 16 on the base plate 20. The backward movement of the lifting member 5 is limited by a stud 17, which is vertically adjustable in the base plate and locked in stopping position by means of a surrounding elastic friction ring 18, placed between two walls in the plate 20.

The lifting member 5 is connected to the stopping member 9, 11 by means of spiral springs 21, which are stretched at the forward movement of the lifting member whereby also the stopping member obtains a tendency of moving forward, when the resistance acting upon the said member ceases.

About in the middle of the longitudinal sides of the base plate 20 two projections 29 are arranged, which determine the position of the plate in relation to the rail, when the base plate is brought under the latter. In the middle of the base plate there is further an opening 30 for the hook shaped part 2 of the lever 1.

The teeth 10 are arranged upon special lists 35, which on the underside are provided with studs 36, corresponding to borings in the plates 9, in which borings they after insertion may be locked by means of screws 37 inserted from the side of the plates. The lists thus are exchangeable.

In using the apparatus the two members 5 and 9, 11 must be drawn backward on the base plate 20 so far as possible, whereupon the said plate 20 is pushed under the rail 40 until the projections 29 bear against the foot of the rail. The studs 4 of the lever 1 now are placed in the undermost notches 8 and the lifting member 5 is pushed forward, so that the hook shaped end of the lever 1 grasps under the foot of the rail. According as the rail now is lifted by the lever the stopping member

on account of the springs 21 is brought forward under the foot of the rail and supports it, if the lifting operation is interrupted.

5 Having now particularly described the nature of our invention and the manner of its operation, what we claim is:

1. A lifting apparatus for railway tracks, comprising a base plate, a lifting member movable thereon and consisting of two firmly united plates situated at a distance from one another and provided with a series of notches, a movable stopping member, consisting of two united plates one on each side of the lifting member and each provided with teeth the said two members being connected by springs which are stretched at a forward motion of the lifting member and thereby tend also to move the stopping member forward, and a detachable lifting lever between the two plates of the lifting member, the lifting member being provided with projections, engaging a groove in the upper part of the base plate.

23 2. A lifting apparatus for railway tracks, comprising a base plate, a lifting member movable thereon and consisting of two firmly united plates situated at a distance from one another and provided with a series of notches, a movable stopping member, consisting of two united plates one on each side of the lifting member and each provided with teeth the said two members being connected by springs which are stretched at a forward motion of the lifting member and thereby tend also to move the stopping member forward, and a detachable lifting lever between the two plates of the lifting member, the said lever being provided with studs to be placed in the notches of the lifting member and the two members being adjustably as well as detachably connected with one another by a pin and slot connection.

3. A lifting apparatus for railway tracks, comprising a base plate, a lifting member movable thereon and consisting of two firmly united plates situated at a distance from one another and provided with a series of notches, a movable stopping member, consisting of two united plates one on each side of the lifting member and each provided with teeth the said two members being connected by springs which are stretched at a forward motion of the lifting member and thereby tend also to move the stopping member forward, and a detachable lifting lever between the two plates of the lifting member, the said lever being provided with studs to be placed in the notches of the lifting member, the two members being adjustably as well as detachably united by a cross piece between the two plates of the stopping member passing through slots in the lower back ends of the two plates of the lifting member.

65 4. A lifting apparatus for railway tracks,

comprising a base plate, a lifting member movable thereon and consisting of two firmly united plates situated at a distance from one another and provided with a series of notches, a movable stopping member, consisting of two united plates one on each side of the lifting member and each provided with teeth the said two members being connected by springs which are stretched at a forward motion of the lifting member and thereby tend also to move the stopping member forward, and a detachable lifting lever between the two plates of the lifting member, the lifting member being provided with projections, engaging a groove in the upper part of the base plate.

5. A lifting apparatus for railway tracks, comprising a base plate, a lifting member movable thereon and consisting of two firmly united plates situated at a distance from one another and provided with a series of notches, a movable stopping member, consisting of two united plates one on each side of the lifting member and each provided with teeth, the said two members being connected by springs which are stretched at a forward motion of the lifting member and thereby tend also to move the stopping member forward, and a detachable lifting lever between the two plates of the lifting member, the said lever being provided with studs to be placed in the notches of the lifting member and the two members being adjustably as well as detachably connected with one another by a pin and slot connection.

6. A lifting apparatus for railway tracks, comprising a base plate, a lifting member movable thereon and consisting of two firmly united plates situated at a distance from one another and provided with a series of notches, a movable stopping member consisting of two united plates one on each side of the lifting member and each provided with a toothed and exchangeable list, the said two members being connected by springs which are stretched at a forward motion of the lifting member and thereby tend also to move the stopping member, and a detachable lifting lever between the two plates of the lifting member, the said lever being provided with studs to be placed in certain of the notches of the lifting member.

7. A lifting apparatus for railway tracks, comprising a base plate, a lifting member movable thereon and consisting of two firmly united plates situated at a distance from one another and provided with a series of notches, a movable stopping member consisting of two united plates one on each side of the lifting member and each provided with a toothed and exchangeable list provided with studs adapted to engage corresponding borings in the wall of the stopping member and to be locked thereto by means of screws, the said two members being connected by springs which are stretched

at a forward motion of the lifting member and thereby tend also to move the stopping member, and a detachable lifting lever between the two plates of the lifting member, 5 the said lever being provided with studs to be placed in certain of the notches of the lifting member.

8. A lifting apparatus for railway tracks, comprising a base plate, a lifting member 10 movable on the base plate and consisting of two firmly united plates situated at a distance from one another and provided with a series of notches, a movable stopping member, consisting of two united plates one on 15 each side of the lifting member and each provided with teeth the said two members being connected by springs which are stretched at a forward motion of the lifting member and thereby tend also to move the stopping member forward, a detachable lifting lever 20 between the two plates of the lifting member, the said lever being provided with studs to be placed in the notches of the lifting member, a stop at the one end of the base 25 plate and at the other end locking means for preventing an unintentional separation of

the stopping and lifting members and the plate.

9. A lifting apparatus for railway tracks, comprising a base plate having at the one 30 end a stop and at the other end a vertically adjustable stud locked by a surrounding friction ring which is held by the base plate, a lifting member movable thereon and consisting of two firmly united plates situated 35 at a distance from one another and provided with a series of notches, a movable stopping member, consisting of two united plates one on each side of the lifting member and each provided with teeth the said two members being connected by springs which are stretched at a forward motion of the lifting member and thereby tend also to move the stopping member forward, and a detachable lifting lever 40 between the two plates of the lifting member, the said lever being provided with studs to be placed in the notches of the lifting member. 45

In testimony whereof we have signed our names to this specification.

ERIK TIMANDER.

GÖSTA TIMANDER.
